GEORGE B. EMERSON AND CHARLES E. BUYSSE, OF DETROIT, MICHIGAN.

MIXING-VALVE.

1,351,236.

Specification of Letters Patent. Patented Aug. 31, 1920.

Application filed September 16, 1916. Serial No. 120,441.

To all whom it may concern:

Be it known that we, GEORGE B. EMERSON and CHARLES E. BUYSSE, citizens of the United States, residing at Detroit, county of Wayne, State of Michigan, have invented a certain new and useful Improvement in Mixing-Valves, and declare the following to be a full, clear, and exact description of the same, such as will enable others skilled in the art to which it pertains to make and use the same, reference being had to the accompanying drawings, which form a part of this specification.

Our invention relates to air and gas mixers and an object of our improvements is to provide an improved suction mixing valve for gas engines in which the air and gas will be efficiently mingled and the proportions of the same accurately gaged and maintained.

We secure this object in the device illustrated in the accompanying drawings in which,

Figure 1 is a plan view of a valve embodying our invention.

Fig. 2 is a central sectional elevation of the same.

Fig. 3 is an elevation looking from the right of Fig. 2.

Fig. 4 is a section on the line D—D Fig. 2, looking from above said line.

Fig. 5 is a diagrammatic view of the valve with a part of the intake pipe cut away to show the valve for balancing the pressure from the gas supply.

a is the casing of the valve having a contracted, or venturi, portion *a*² and a flange *a*³ by which the valve is secured to the intake of the engine. *b*³ are a plurality of apertures formed at various points, substantially symmetrically located, through the wall of the casing *a* above the contracted portion *a*² and communicating immediately with the outer air. *b* is a hollow projection from the casing *a* provided with internal screw threads by which the valve is connected to the source of gas supply by the usual piping. *b*² is an aperture formed through the shell of the casing *a* and opening to the interior of the projection *b*.

c is a plug fitting and adapted to turn in the casing *a* and provided with apertures *c*⁴ adapted to register with the apertures *b*³ in the casing *a*. As the plug *c* is turned the

apertures *c*⁴ register more or less with the apertures *b*³ to vary the area of passage by which the air enters the casing *a*. *c*² is a similar aperture through the wall of the plug *c* adapted to register more or less with aperture *b*² to vary the area of passage for the gas. The aperture *c*² opens to a lateral passage in the plug *c* which at the center of said plug turns downward in a passage coaxial with said plug which is extended in a pipe *c*³ to a point just below the contraction *a*² in the casing *a*. *c*⁴ is a retaining ring for holding the plug *c* in position and *c*⁵ is a handle by which the plug *c* may be turned.

*a*⁷ (Figs. 3 and 4) is a small auxiliary opening located at the side of one of the openings *b*³ and adjacent thereto. As the plug *c* is turned toward the side at which the small aperture *a*⁷ is located to contract the area of passage of air and gas through the opening *b*³ *c*⁴ and *b*² *c*², respectively, the aperture *a*⁷ remains in full registry with an aperture *c*⁴ in the plug so that the air is shut off less rapidly than the gas when the parts are adjusted for running the engine "idling."

*a*⁶ *a*⁶ are conventional set screws by which the extent of travel of the handle *c*⁵ and the turning of the plug *c* is adjusted.

Inasmuch as there is usually a slight pressure of gas above that of the atmosphere, a ball valve *e* (Fig. 5) is interposed in the gas intake passage to balance such pressure.

It will be observed that the extension *c*³ carries the delivery end of the gas passage below the contraction *a*² in the casing *a* thus as air is sucked from said casing the increased rush of air through the venturi passage draws the gas from the passage *c*³ at a greater rate and maintains the proper mixture and the passages for delivery of gas and air coact with each other.

The delivery opening from the passage *c*³ extends into or a little beyond the contraction of the delivery passage for air so that the air and gas are simultaneously and equally acted upon by the suction of the engine.

What we claim is:

In an apparatus of the kind described, a casing having an air passage formed therein, means for delivering air into said passage, said passage being contracted toward the delivery end thereof beyond the portion

of said passage to which air is admitted, a pipe c^3 within the larger portion of said air passage and extending into and beyond the most contracted portion thereof at its delivery and, means for supplying gas to the inner portion of said pipe, said casing being adapted to be secured to the intake of the

engine so that the suction of the engine shall come directly on the delivery end of said air passage.

In testimony whereof, we sign this specification.

GEORGE B. EMERSON.
CHARLES E. BUYSSSE.
